MACHINE FOR PRODUCING RANDOM FIBER WEBS

Dennis E. Wood, Penfield, N.Y., assignor to Curlator Corporation, East Rochester, N.Y., a corporation of New York

Filed June 10, 1969, Ser. No. 17,522

Term of patent 14 years

Int. Cl. D15—08

U.S. Cl. D92—15

FIG. 1

Des. 220,026

PAGE 2

FIG. 2

FIG. 3

FIG. 4

FIG. 5

FIG. 1 is a top view of a machine for producing random fiber webs showing my new design;

FIG. 2 is a side elevational view thereof;

FIG. 5 is an end elevational view of the end opposite that shown in FIG. 2;

FIG. 4 is an end elevational view; and

FIG. 5 is an end elevational view of the end opposite that shown in FIG. 4.

I claim:

The ornamental design for a machine for producing random fiber webs, as shown.
